UNITED STATES PATENT OFFICE

WALTER NICOLET, OF LEIPZIG, GERMANY

ART OF WEAVING

Application filed December 7, 1925, Serial No. 73,718, and in Germany December 18, 1924.

• My invention refers to the art of weaving and it particularly concerns means whereby the speed of weaving and in accordance therewith the quantity of woven fabric produced per unit of time are materially increased. These means comprise improvements in looms, which will be described more fully hereinafter.

In the looms hitherto in use, the warp threads extend from the warp beams in one direction close together to the leaves and the mounting and across them and the reed to the woven fabric. By raising part of the warp threads and lowering the rest, a shed is formed in which the weft is inserted by the shuttle. The thread of the weft is then set on the fabric by swinging the reed and is tied up by changing the shed, whereupon the same procedure is gone through anew.

20 The present invention is designed to materially increase the output of a loom of this kind. In accordance with this invention one part of the warp threads is placed at an angle to the rest of the threads in front of 25 the path described by the shuttle in such manner that the two groups of warp threads form a second shed which is not changed in this place and into which, while the shuttle is driven through the ordinary shed, a second shuttle is driven which also inserts a weft. The reed customarily employed for casting the weft onto the fabric is preferably replaced by combs.

In the drawings affixed to this specification and forming part thereof the new method of weaving and a loom embodying my invention are illustrated diagrammatically by way of example.

35 In the drawings
40 Figs. 1 and 2 are diagrams illustrating different positions of the warp threads as arranged in accordance with this invention.

Fig. 3 is a diagram illustrating a piece of fabric manufactured in accordance with the 45 novel method.

Fig. 4 is a front elevation and

Fig. 5 is a rear elevation, with some parts broken away, of the loom.

Fig. 6 is a cross-section on the line VI—VI
50 in Fig. 4 drawn to a larger scale.

Fig. 7 is a front elevation of one of the shuttle boxes arranged at the ends of the machine, drawn to a larger scale also.

Fig. 8 is a cross-section on the line VIII—VIII in Fig. 7 and

Fig. 9 is a perspective view showing in a diagrammatic manner and at a larger scale the way of inserting the weft in the shuttle.

Fig. 10 is a diagram of connections illustrating electric means for controlling the operation of the shuttles in order to avoid tearing of the threads.

Referring first to Figs. 1 and 2 of the drawings, 1 and 2 are two warp beams disposed at different levels, one above the other, and 3 and 4 are the two groups of warp threads wound upon these beams. The warp threads 3 extend through eyes 5 formed at the ends of the teeth of a comb 5, the warp threads 4 through eyes 6 at the ends of the teeth of a comb 7, this latter being positioned to the rear of comb 5 viewed in the direction towards the fabric. The warp threads 4 extending through comb 7 are so guided that they extend at an angle to the warp threads 3 in front of comb 7. This is obtained by the positioning of warp beam 2 at a higher level than warp beam 1. However, if both groups of warp threads are arranged on a single warp beam, the same effect can be obtained by leading the warp threads 4 over guide sheaves disposed above the warp threads 3.

The two groups of threads thus permanently form in front of comb 7 a shed which is open towards the warp beams 1 and 2. Comb 5 and, if desired, also comb 7 are movable in the vertical direction. In the lowermost position of comb 5, the warp threads 3 extend some distance from the warp threads 4 underneath the eyes of comb 7. In this position of the threads the shed spoken of above is open down to the fabric 8. If, however, the warp threads 3 are raised by comb 5, they enter into the gaps of comb 7, (which may at the same time move in the direction towards comb 5) and the groups of threads 3 and 4 are thus caused to cross, whereby another shed is formed to

the rear of comb 7 (Fig. 2). According to the present invention a weft thread is passed simultaneously through each of these sheds, a shuttle 9 (Fig. 2) introducing the weft 11, the shuttle 10 the weft 12. Shortly before the warp threads 3 are lowered and the warp threads 4 raised from the position shown in Fig. 2, the weft 11 entered in the shed to the rear of comb 7 is cast onto the edge of the fabric 8 by a reed 13. By lowering the warp threads 3 and, if desired, raising the threads 4 the shed formed to the rear of comb 7 is opened, the weft 11 which had been cast onto the fabric being now tied up by the warp threads 3 and 4 which now cross directly in front of this weft. On the warp threads 3 having again assumed their lowermost position and the threads 4 their highest position (Fig. 1) the shed formed between the comb 7 and the warp beams is now opened towards the fabric 8. The weft 12 entered into this shed has been moved during the movement of combs 5 and 7 by a fork 14 up to the level of comb 7 and after the shed has been opened towards the fabric 8, it is cast onto the fabric by means of a separate reed 15 moving past and underneath comb 7. The two reeds 13 and 15 must be operated in such manner that the first reed does not form an obstacle to the casting on of the second weft by the other reed 15. Reed 13 must be caused to move its weft in contact with the fabric at the moment when the groups of threads 3 and 4 are caused to cross; the same holds good for weft 15, or else the sheds would not be cleared for the next succeeding weft. As the warp threads 3 are raised again from their position shown in Fig. 1, the warp threads 4 being at the same time lowered, if desired, they will act towards tying up the weft 12 when crossing the threads 4 and once more forming a shed to the rear of comb 7.

While the shed formed to the rear of comb 7 is alternately formed and opened, the shed in front of the comb is permanently formed, being alternately closed or opened by the comb 7. By simultaneously entering two wefts which may be formed of a single thread or of a plurality of threads, in two juxtaposed sheds the output of the loom is increased correspondingly. Moreover the edge portion of the fabric is firmly tied up by the weft 12 inserted in the always open shed, as can be seen by inspecting Fig. 3, which illustrates a fabric produced in this manner and in which two weft threads have been entered in each shed at each operation, these weft threads being taken from stationary bobbins.

The bobbins as well as the shuttles may be formed in a different manner. I can either use freely travelling shuttles or shuttles travelling between guides. I can

weave with weft material disposed in the shuttles or I can employ weft material taken from stationary bobbins. This latter mode of proceeding is preferable inasmuch as in this case the shuttle can be kept materially lower and in consequence thereof the shed may be kept lower also. However, this can only be done provided that the character and purpose of the fabric admits of it. The shuttles can be moved by means of drivers, springs or in any other suitable way.

In the loom illustrated in Figs. 4-10 and which is adapted for carrying out my novel method of weaving, stationary bobbins 16, 17, 18 are provided and both shuttles 9 and 10 move between guides 19 and 20 respectively. The guiding means 19 provided for shuttle 9 are formed by two parallel rails 19^a and 19^b located close together and hinged to each other by their upper edges, these rails carrying two rows of laminae 19^c disposed like the teeth of a comb. Those parts of the two rows of laminae which face each other are provided with indentures cooperating with each other to form a guide channel for the shuttle 9 which, as shown more particularly in Fig. 9 has the form of a thin metal rod with a gripping hook 9^a projecting from each end of the rod. The shuttle 9 is actuated by a pair of strikers 22 (Fig. 7) one striker being disposed on each side of the loom. These strikers are placed under the action of springs 21 and are guided in tubes 24 adjoining the shuttle boxes 23. Each striker 22 has mounted in its middle a cross pin 25 projecting on either side from a slot formed in the tube 24. The driver spring on one side of the loom is placed under tension by means of an angle lever 26, the forked end of which applies itself against the cross pin 25 while its other arm is pivoted to a rod 28, the lower end of which is influenced by an eccentric disc 27 mounted on an intermediate shaft 30 (Fig. 7) driven from the main shaft 29 with one half of the speed of this latter. When the lever 26 is rocked by the rod 28 and eccentric disc 27, the striker 23 is drawn backwards, the springs 21 being at the same time compressed, and in its rearmost position the striker is locked by means of angle levers 31 with hook-shaped ends which grip the cross pin 25. The compression of the striker spring on the other side of the loom is effected by a lever 26' which is connected with the lever 26 by a rod 32 in such manner that these two levers always move in unison. When lever 26 forces the striker 22 back, lever 26' releases the striker appertaining to it and vice versa. During the backward movement of levers 26 and 26' respectively, after the springs have been compressed, the shuttle 9 is placed in front of the striker 22 ready for striking. Shortly before the lever 26 or 26' has reached its rearmost

position, its forked end meets a check 34 mounted on a rod 33 and thereby displaces this rod in its bearings on the frame 81. The rear end of rod 33 acts by means of a set screw 35 on an arm of the hook-shaped angle levers 31 which lock the striker. In consequence of this movement of rod 33 the hooks 31 are withdrawn, thereby releasing the cross pin 25 and the striker 22 which is now driven forward by spring 21 and strikes the shuttle 9 so as to throw it across the guide 19 towards the opposite side of the loom.

In order to prevent the shuttle from being thrown back when hitting the end wall of the shuttle box 23 on the opposite side, each box is provided with a leaf spring 36 acting towards braking the shuttle. The same springs are also active when the shuttle is thrown forward, by preventing it from prematurely separating from the striker 22, so that the force of the spring is fully utilized.

When the shuttle is thrown from the box 23, the gripping hook 9^a which is nearest to the striker 22 grips the weft 11 extending in the shuttle box across the path of the gripping hooks and pulls it in the form of a loop across the shed (Fig. 9). On the shuttle entering the opposite shuttle box the weft extended across this box is simply moved aside by the wedge action of the outer edge of the front hook of the shuttle. However, after this hook has passed below it, the weft at once returns into its initial position so that on the shuttle being thrown back, it is securely gripped by the jaw of the shuttle hook. The weft carried along by the hook of the shuttle after this latter has passed through the shed, is pulled off the hook when the weft is cast onto the fabric by the reed 13.

The means 20 for guiding the shuttle 10 (Fig. 6) are formed as a tube slotted at the bottom. The shuttle 10 has the form of a thin metal rod to which is fixed an eye 37 extending outwards through the slot. This eye 37 embraces the weft 12 taken from the bobbin 18. If, as assumed in Figs. 1 to 3, two weft threads shall be introduced at each operation into the shed, which is permanently open towards the warp beams, two such eyes 37 must be mounted on the shuttle 10 and two bobbins 18 must be provided for in the loom.

The shuttle 10 is set moving by means which exactly correspond to those provided with respect to shuttle 9. As shown in Fig. 8 they comprise a striker 22' guided in a tube 24' and acted upon by a spring, this striker being pulled back against the action of this spring by a forked lever 38 gripping cross pins 25 mounted on the striker, which is locked in this position by a hook-shaped angle lever 31'. It is unlocked by the forked lever 38 in swinging backward meeting a

check 34' and displacing a rod 33' carrying the check, whereby the rod releases the lever 31' by means of a set screw 35'. Lever 38 which serves for compressing the springs acting on the shuttle 10 is directly coupled with the levers 26 and 26' serving for compressing the springs acting on the shuttle 9.

The raising and lowering of the warp threads 3 is effected in this loom by means of laminae 40 extending upwards from a rail 39 (Fig. 6), these laminae replacing the comb 5 illustrated in the diagrams of Figs. 1 and 2. The threads 3 extend through eyes formed on the free ends of the laminae 40. Similar means comprising laminae which, however, should extend downwards, may be provided for guiding the warp threads 4, which enter between the threads 3 at a steep angle. I prefer, however, to employ for this purpose the laminae 19^a forming part of the guide rail 19^b for shuttle 9, which face the warp beams and which need merely be a little longer than laminae 19^a of the other rail 19^a and need merely be provided with eyes on their free ends. Rail 39 is suspended from one end of two levers 41, each of which rests with a roller on a cam disc 42 mounted on the main shaft 29, the cams of this disc being so shaped that rail 39 is lifted and lowered as required, whereby the warp threads 35 are raised and lowered correspondingly. In order to obtain the correct guiding of the warp threads 3, I prefer fixing to the rail 39 a comb 43, through each gap of which extends a warp thread 3. In order to form the shed nothing is required but the raising and lowering of the warp threads 3. In order, however, to be able to form the shed as quickly as possible and in order further to shorten the movement of rail 39, I prefer moving the warp threads 4 in opposition to the warp threads 3, which can be effected by lowering and raising the rails 19^a and 19^b, the shuttle box 23 partaking in this movement, if necessary. To this end the rails 19^a, 110 19^b are also suspended from the ends of two levers 44 (Fig. 6) which are connected by chains 46 passing over a sleeve 45 with levers 41 in such manner that they move in opposite directions, when the levers are rocked.

115 47 is a further comb fixed also to lever 44 and serving for securing the correct guiding of the warp threads.

The reed 13 which pushes the thread 11 towards the fabric projects from above into 120 the group of warp threads 3 behind the weft 11 which has just been introduced. The reed is moved towards the fabric and after having cast the weft on is pulled back from between the warp threads in upward direction and 125 returned above the warp threads into its initial position close to the guide 19. The weft 11 being here introduced in the form of a loop, a double reed is employed in this case, one projecting behind one, the other 130

behind the other branch of the loop. After the weft has been introduced the distance between the two branches of the loop formed by the weft is greater than allowed in the finished fabric and for this reason the two parts of the double reed are movable relatively to each other. When entering the warp they are spaced apart a distance equal to the width of the loop, however, near the end of their movement towards the fabric their distance diminishes so far that the two branches of the loop when reaching the fabric assume the correct distance relative to each other. The double reed 13 is moved in such manner by the following means: the two reeds 13 are mounted at the ends of two levers 48 (Figs. 4 and 6), which are mounted for rotation like a pair of scissors at the end of a double armed lever 49 rotatable about a fixed point of the machine frame. The free ends of the two levers 48 are normally forced asunder by a spring 50, so that the pair of scissors is opened and the two reeds 13 are spaced widely apart. The free end of the double-armed lever 49 is pivoted by a rod 51 to one arm of an angle lever 53 mounted for rotation on a fixed shaft 52, the other arm of the angle lever carrying a roller which is in contact with a cam disc 54 mounted on the main shaft 29. This cam disc by acting on the lever 53, rod 51 and lever 49, causes the double reed 13 to be raised and lowered relative to the warp threads. That lever 48, the lower part of which adjoins the guide 19, is coupled by means of a link 55 with one end of a double-armed lever 57 mounted for rotation about a point 56 of the machine frame, the other end of lever 57 carrying the roller 58 which contacts with a cam disc 59 mounted on the main shaft 29. During the rotation of the main shaft 29 the cam disc 59 causes lever 57 to rock, and this lever sets one of the levers 48 rocking by means of the connecting rod 55, the other lever 48 partaking in the rocking movement owing to the connection established by the spring 50. In consequence of this movement, when the double reed 13 projects into the group of warp threads the lower arms of the levers 48 are pulled towards the fabric and during this movement act towards casting the weft 11 in front of them onto the fabric. If that lever 48 which is carried along by spring 50, has cast the part of the loop in front of it onto the fabric it is stopped by a check 60, so that only the lever 48 which is coupled with lever 57 by the connecting rod 55 can move on, stretching spring 50 and can carry the part of the loop adjoining it into the correct position close to the other part which has already been applied against the fabric. After this has been effected the double reed 13 is withdrawn from between the warp threads and the pair of coupled levers 48 is

swung back towards the guide 19 outside the warp threads. In order to lessen the distance through which the reed 15 is moved in casting the weft 12 introduced into the permanently open shed onto the fabric, the weft 12, as already described above, is carried by means of forks 14 substantially to the level of the weft 11. The toothed forks 14 mounted on both sides of the loom do not move uniformly. The carrying forward of the weft is always effected only by the forks on one side of the loom for the reason that the weft is passed through one time from the right and the other time from the left and is held applied against the fabric on that side from which the shuttle is struck, by the preceding bindings so that the weft must be cast on only on the other side. Each of the forks 14 on either side is fixed to the end of an angle lever 61, the other end of which carries a roller in contact with a cam disc 62 on the intermediate shaft 30. The two cam discs 62 are staggered 180°. Inasmuch as the shaft 30 rotates only at half the number of revolutions of the main shaft 29, each cam disc 62 becomes operative only during every second rotation of the main shaft 29 and the staggered position of the two cam discs has for its result that while one weft is passed through the shed, the fork 14 on one side of the loom and during the passing of the next succeeding weft, the fork 14 on the other side will carry that end of the weft 12 which is not applied against the fabric into reach of reed 15.

Reed 15 projects towards the warp threads from below, it forces the weft 12 placed in front of it towards the fabric, is withdrawn in downward direction from between the warp threads and it is carried back into its initial position underneath the warp threads. It is mounted on one end of an angle lever 64 acted upon by a spring 63 and having its angle point pivoted to the end of a lever 65 which is loose on shaft 52 and is influenced by a cam disc 66 fixed on the main shaft 29, so as to cause the reed 15 to be raised and lowered. That arm of angle lever 64 which carries the reed 15 is applied by the spring 63 against a roller 67 mounted on the same journal which carries the roller 58 of lever 57. On this lever being rocked by the cam disc 59, that arm of the angle lever 64 which carries reed 15 follows this movement, thereby causing the reed 15 to reciprocate in horizontal direction. The cam disc 59 can be used for effecting the reciprocating movement of reed 13 as well as of reed 15 inasmuch as the two reciprocate simultaneously but in opposite direction.

It may happen that the shuttle is braked while passing through the guide and jams within this latter. As far as the shuttle is concerned this is of little importance in-

asmuch as it is arranged outside the closed shed formed by the two groups of warp threads and things can easily be set right inasmuch as this shuttle is always readily accessible. However, if the shuttle 9 should jam it will disturb the opening of the shed and this would lead to an entangling and tearing of the warp threads. For this reason means are provided whereby, as long as the shuttle 9 is not at rest in the shuttle box 23, the rail 39 which moves the warp threads 3, and the comb 43 mounted thereon are prevented from being lowered. These means consist of two angle levers 69, one on each side of the loom, these levers being pivoted to the machine frame at 68 and being influenced by a spring 70 at one end, the other end projecting below a pin 71 mounted on the lever 41 which carries the rail 39 and cam 43. The other end of the lever 69 is further connected with the iron core 73 of a solenoid 72. As soon as the shuttle 9 enters the shuttle box on one side of the loom the circuit 74 (Fig. 10) containing the two solenoid coils 72 is closed, whereby the iron cores 73 are attracted which now cause the angle lever 69 to rock so as to release levers 41, which are now free to be lowered in accordance with the shape of the cam discs 42. The circuit is closed by means of two switches connected in parallel, one such switch being mounted on each side of the loom. Each switch consists of a double-armed lever 75 having a blade 76, which cooperates with a pair of contact springs 77. A spring 78 acting on one end of the contact lever 75 tends to normally pull the blade 76 away from the contact springs 77. That end of the lever 75 on which the spring 78 acts, projects into the path of the gripper hooks of shuttle 9 in the shuttle box and is forced back by the shuttle against the action of spring 78, whereby the blade 76 is forced in contact with the springs 77, thereby closing the circuit. The parallel circuit containing the other switch remains open during this time. As soon as the shuttle 9 has again been thrown from the shuttle box 23, spring 78 acts towards opening the switch on this side, and on the shuttle entering the shuttle box on the other side, the other switch is closed.

Obviously this electric safety device can also be replaced by another device, for instance a mechanical one.

The warp threads are pulled and the fabric is carried forward as usual by the beam 79 which is driven in a well-known manner from the main shaft 29 by a suitable gearing (not shown), and which also effects the placing of the fabric onto the work beam 80.

The term "shed" as used in the claims is intended to mean a shed adapted for a weft

to be entered therein. The term "shuttle" is meant to include all kinds of picking motions.

I wish it to be understood that I do not desire to be limited to the exact details of constructions shown and described for obvious modifications will occur to a person skilled in the art.

I claim:—

1. The method of producing a fabric by weaving comprising bodily moving one of two groups of warp threads alternately in one and the other direction so as to form in each alternate operation two sheds, a closed shed and an open shed to the rear of said closed shed, and passing a weft thread through the front shed and another weft thread through the rear shed, before the front shed has been dissolved and beating up each weft thread. 75 80 85

2. The method of producing a fabric by weaving comprising bodily moving one of two groups of warp threads alternately in one and the other direction so as to form in each alternate operation two sheds, a closed shed and an open shed to the rear of said closed shed, and simultaneously passing a weft thread through each shed and beating up each weft thread. 90

3. The method of producing a fabric by weaving, comprising bodily moving one of two groups of warp threads extending at an angle to each other alternately in one and the other direction so as to form in each alternate operation two sheds, a closed shed and an open shed to the rear of said closed shed, and passing a weft thread through the front shed and another weft thread through the rear shed, before the front shed has been dissolved and beating up each weft thread. 95 100 105

4. The method of producing a fabric by weaving, comprising bodily moving one of two groups of warp threads extending at an angle to each other alternately in one and the other direction so as to form in each alternate operation two sheds, a closed shed and an open shed to the rear of said closed shed, and simultaneously passing a weft thread through each shed and beating up each weft thread. 110 115

5. The method of producing a fabric by weaving, comprising bodily moving one of two groups of warp threads so as to cause the same to cross the threads of the other group and to form a closed shed in front and an open shed to the rear of the crossing and passing a weft thread through the front shed and another weft thread through the rear shed, before the front shed has been dissolved and beating up each weft thread. 120 125

6. The method of producing a fabric by weaving, comprising bodily moving one of two groups of warp threads so as to cause the same to cross the threads of the other group and to form a closed shed in front 130

and an open shed to the rear of the crossing and simultaneously passing a weft thread through each shed and beating up each weft thread.

7. A loom comprising means for bodily moving one group of warp threads so as to form in each alternate operation two sheds, a closed shed and an open shed to the rear of said closed shed and means for passing a weft thread through the front shed and another weft thread through the rear shed, before the front shed has been dissolved and means for beating up each weft thread.

8. A loom comprising means for bodily moving one group of warp threads so as to form in each alternate operation two sheds, a closed shed and an open shed to the rear of said closed shed, stationary shuttle guiding means permanently arranged in said open shed and means for passing a weft thread through the front shed and another weft thread through the rear shed, before the front shed has been dissolved and means for beating up each weft thread.

9. A loom comprising means for bodily moving one group of warp threads so as to form in each alternate operation two sheds, a closed shed and an open shed to the rear of said closed shed and means for simultaneously passing a weft thread through each shed and means for beating up each weft thread.

10. A loom comprising means for bodily moving one of two groups of warp threads so as to cause same to cross the threads of the other group and means for forming a closed shed in front and an open shed to the rear of the crossing and means for passing a weft thread through the front shed and another weft thread through the rear shed, before the front shed has been dissolved and means for beating up each weft thread.

11. A loom comprising means for bodily moving one of two groups of warp threads so as to cause same to cross the threads of the other group and means for forming a closed shed in front and an open shed to the rear of the crossing and means for simultaneously passing a weft thread through each shed and means for beating up each weft thread.

12. A loom comprising means for forming the warp threads into two groups extending at an angle to each other, means for bodily moving the threads of one group towards and past the threads of the other group and back again so as to form two sheds, a closed shed and an open shed to the rear of said closed shed, means for passing a weft thread through the front shed and another weft thread through the rear shed formed in said warp threads in consequence of such movement of said moving means before the front shed has been dissolved and means for

setting the weft threads in the two sheds onto the woven fabric.

13. A loom comprising means for forming the warp threads into two groups extending at an angle to each other, means for bodily moving the threads of one group towards and past the threads of the other group and back again so as to form two sheds, a closed shed and an open shed to the rear of said closed shed, means for passing a weft thread through the front shed and another weft thread through the rear shed formed in said warp threads in consequence of such movement of said moving means before the front shed has been dissolved and separate means for setting the weft threads in the two sheds onto the woven fabric.

14. A loom comprising two warp beams, means for forming the threads from each beam into a group of their own extending at an angle to the group from the other beam, means for bodily moving the threads of one group towards and past the threads of the other group and back again, means for passing a weft thread through the front shed and another weft thread through the rear shed formed in said warp threads in consequence of a movement of said moving means before the front shed has been dissolved and means for setting the weft threads in the two sheds onto the woven fabric.

15. A loom comprising two warp beams, means for forming the threads from each beam into a group of their own extending at an angle to the group from the other beam, means for bodily moving the threads of one group towards and past the threads of the other group and back again, means for simultaneously passing a weft thread through each of the sheds formed in said threads in consequence of a movement of said moving means and means for setting the weft threads in the two sheds onto the woven fabric.

16. A loom comprising means for forming the warp threads into two groups extending at an angle to each other, a comb with eyes for the threads of one group movable towards and past the threads of the other group, a shuttle guiding rail movable in opposite direction to said comb, means for passing a weft thread through the front shed and another weft thread through the rear shed formed in said threads in consequence of a movement of said comb and rail before the front shed has been dissolved and separate means for setting the weft threads in the two sheds onto the woven fabric and means for beating up each weft thread.

17. A loom comprising means for forming the warp threads into two groups extending at an angle to each other, a comb with eyes for the threads of one

group movable towards and past the threads of the other group, a guide rail movable in opposite direction to said comb, means for passing a weft thread through the front shed and another weft thread through the rear shed formed in said threads in consequence of a movement of said comb and rail before the front shed has been dissolved and two reeds movable substantially in the direction of the threads for setting the weft threads in the two sheds onto the woven fabric and means for beating up each weft thread.

18. A loom comprising means for forming the warp threads into two groups extending at an angle to each other, guiding means for the threads of one group movable towards and past the threads of the other group, said guiding means being formed to also guide a shuttle, means for passing a weft thread through each of the sheds formed in said threads in consequence of a movement of said guiding means and separate means for setting the weft threads in the two sheds onto the woven fabric.

19. A loom comprising means for forming the warp threads into two groups extending at an angle to each other, guiding means for the threads of one group, said guiding means being shaped to conjointly form a groove extending at right angles to the warp threads for guiding a shuttle, means for passing a weft thread through each of the sheds formed in said threads in consequence of a movement of said guiding means and separate means for setting the weft threads in the two sheds onto the woven fabric.

20. In a loom comprising means for forming the warp threads into two groups extending at an angle to each other, a pair of cooperating combs hinged together, a row of laminæ on each comb, the laminæ on one comb being formed with eyes for guiding a group of warp threads, the laminæ on both combs being formed in their adjoining parts with indentures combining to form a guide channel for a shuttle.

21. A loom comprising means for forming the warp threads into two groups extending at an angle to each other, guiding means for the threads of one group movable towards and past the threads of the other group, thread separating means rigidly combined with said guiding means, means for simultaneously passing a weft thread through each of the sheds formed in said threads in consequence of a movement of said guiding means and separate means for setting the weft threads in the two sheds onto the woven fabric.

22. A loom comprising means for forming the warp threads into two groups extending at an angle to each other, guiding means for the threads of one group movable

towards and past the threads of the other group, thread separating means rigidly combined with said guiding means, a rock lever carrying said guiding and separating means, a cam disc associated with said lever to rock same, means for simultaneously passing a weft thread through each of the sheds formed in said threads in consequence of a movement of said guiding means and separate means for setting the weft threads in the two sheds onto the woven fabric.

23. A loom comprising means for forming the warp threads into two groups extending at an angle to each other, separate guiding means for the threads of each group, the guiding means of each group being movable towards and past the threads of the other group, means for moving the guiding means of one group, means for connecting the guiding means of this group with those of the other group in such manner as to simultaneously move the two guiding means and groups of threads in opposite direction, means for simultaneously passing a weft thread through each of the sheds formed in said threads in consequence of a movement of said guiding means and separate means for setting the weft threads in the two sheds onto the woven fabric.

24. A loom comprising means for forming the warp threads into two groups extending at an angle to each other, separate guiding means for the threads of each group, the guiding means of each group being movable towards and past the threads of the other group, means for moving the guiding means of one group, a sheave, a flexible member suspended from said sheave and connecting the guiding means of this group with those of the other group in such manner as to simultaneously move the two guiding means and groups of threads in opposite direction, means for simultaneously passing a weft thread through each of the sheds formed in said threads in consequence of a movement of said guiding means and separate means for setting the weft threads in the two sheds onto the woven fabric.

25. A loom comprising means for forming the warp threads into two groups extending at an angle to each other, separate guiding means for the threads of each group, the guiding means of each group being movable towards and past the threads of the other group, means for moving the guiding means of one group, a separate lever carrying the guiding means of each group, means for connecting said levers in such manner as to simultaneously move the two guiding means and groups of threads in opposite direction, means for simultaneously passing a weft thread through each of the sheds formed in said threads in consequence of a movement of said guiding means and sepa-

rate means for setting the weft threads in the two sheds onto the woven fabric.

26. A loom comprising means for moving the warp threads so as to form in each operation two sheds, one to the rear of the other, means comprising a shuttle for passing a weft thread through each shed, a shuttle guiding channel being formed in said shed forming means and an eye on said shuttle projecting from said channel and means for beating up each weft thread.

27. A loom comprising means for moving the warp threads so as to form two sheds, one to the rear of the other, in each operation, two shuttles, two juxtaposed shuttle boxes, a spring-actuated shuttle striker associated with each shuttle box and common controlling means for said strikers and means for beating up each weft thread.

28. A loom comprising means for moving the warp threads so as to form two sheds, one to the rear of the other, in each operation, two shuttles, two juxtaposed shuttle boxes, a spring-actuated shuttle striker associated with each shuttle box, two forked levers coupled with each other for controlling said strikers and a common actuating means for said levers and means for beating up each weft thread.

29. A loom comprising means for moving the warp threads so as to form two sheds, one to the rear of the other, in each operation, two shuttles, a weft thread associated with each shuttle, means for simultaneously moving said shuttles and weft threads in juxtaposition across said loom and means for shifting the weft thread governed by one shuttle towards the weft thread governed by the other shuttle and means for beating up each weft thread.

30. A loom comprising two groups of warp threads, means for moving said groups so as to form in each operation two sheds, one to the rear of the other, means for locking said moving means in operative position, a shuttle and electric means arranged to be actuated by said shuttle for releasing said moving means and means for beating up each weft thread.

31. A loom comprising two groups of warp threads, means for moving said groups so as to form in each operation two sheds, one to the rear of the other, means for locking said moving means in operative position, a shuttle, a solenoid adapted to act on said locking means and a switch device adapted to control said solenoid and to be actuated by said shuttle and means for beating up each weft thread.

32. The method of producing a fabric by weaving comprising positively guiding one of two groups of warp threads alternately in one and the other direction so as to simultaneously form in each alternate operation two sheds, one to the rear of the other, pass-

ing a weft thread through the front shed and another weft thread through the rear shed, before the front shed has been dissolved, casting on the weft thread in the front shed, opening said front shed and 70 beating on the weft thread in the rear shed.

In testimony whereof I affix my signature.

WALTER NICOLET.
